UNITED STATES PATENT OFFICE.

ABRAHAM SHAPIRO, OF MINNEAPOLIS, MINNESOTA.

COMBINATION VENTILATED LAUNDRY STOVE AND BOILER.

1,233,716.

Specification of Letters Patent.

Patented July 17, 1917.

Application filed April 8, 1916. Serial No. 89,952.

To all whom it may concern:

Be it known that I, ABRAHAM SHAPIRO, a citizen of the United States, residing at Minneapolis, in the county of Hennepin and 5 State of Minnesota, have invented certain new and useful Improvements in Combination Ventilated Laundry Stoves and Boilers, of which the following is a specification.

My invention relates to improvements in 10 combination ventilated laundry stoves and boilers, its object being to provide an improved construction of laundry stove constructed to be particularly efficient in connection with a coöperating boiler as well as 15 adapted for other uses.

To this end the invention consists in the construction, combination, and arrangement of parts hereinafter described and claimed.

In the accompanying drawings forming 20 part of this specification,

Figure 1 is a side elevation of my improved stove;

Fig. 2 is a section on line 2—2 of Fig. 1;

Fig. 3 is a section on line 3—3 of Fig. 2;

25 Fig. 4 is a plan view of a supporting rim; and

Fig. 5 is a detail of a grate.

Referring to the drawings, A represents the stove body preferably formed of sheet 30 metal having a solid bottom formed with inlet air openings 2, the whole being supported upon legs 3. Supported in the upper open top of the body of the stove and forming the upper end thereof is a rim portion

35 4 having at its lower end an inward flange 5 and at its upper end an inwardly extending flange 6. A removable flat rim 7 rests upon the flange 5 and is formed with a plurality of openings 8. An outlet pipe 9 pro-

40 vided in rim 4 leads from one side of the space above the rim 7. In this connection it will be noted that the openings provided in one side of the rim 7, on the side of the boiler adjacent the outlet 9, are much smaller

45 than those on the opposite side, as depicted in Fig. 3, whereby the heat which starts to travel the shorter path, as the natural tendency is, will be damped by reason of the small openings 8. Thus, the heat will be

50 deflected to the longer path around the far side of the boiler and thereover, the larger openings 8 being so provided to increase the draft and thereby equalize the passage of the heat up the sides of the boiler. Extending

55 inwardly from the bottom of the side wall of the stove is a plurality of brackets

10 adapted to support a central grate 11 and also to form a support for a boiler 12. The upper end of the boiler stands when in position a short distance below the top of the rim 60 portion 4. The opening in rim 13 is substantially the same size as that of the boiler so that the same cover 14 may be utilized for a closure both for the boiler and the rim 65 13 or stove. The rim 13 being arranged above the top of the boiler, it is apparent that the cover 14, when supported by said rim, will be spaced above the top of the boiler to permit of the heated gases passing over the boiler, as indicated by arrows in 70 Fig. 2. Adapted to rest upon the flange 6 is a second rim 13 adapted to form a support for a cover 14. The ends of the rim portion 4 of the stove are formed with recessed portions 15 to receive the handles 16 75 upon the ends of the boiler. Positioned within the stove body below the grate 11 in a suitable manner is a burner 17 supported by the inlet fuel pipe 18 extending inwardly through the side of the stove body, as shown 80 in Fig. 2. I preferably employ two of these burners as shown in Fig. 3 connected with a suitable supply pipe 18 separated therefrom by controlling valves 19. I also, as shown in Fig. 1, provide the stove with a 85 side door 20 by means of which access will be secured to the interior of the stove body, as where it is desired to place flatirons, etc., upon the grate 11 when the boiler is not in position.

90 In operation, with the boiler in position and the cover 14 supported above the same, as shown in Fig. 2, the heat from the burner 17 will directly heat the bottom of the boiler and pass through the space between the 95 boiler and side wall of the stove and through the openings 8 and over the top of the boiler outwardly through the outlet pipe 9. This gives the maximum heating effect as well as carrying the steam from the boiler outwardly through the discharge pipe 9. When it is desired to remove the boiler the cover 14 and supporting rim 13 may be taken off and the boiler lifted out of the stove, the recess 15 allowing the hands being inserted 100 to grasp the handle 16. Different sized rims 7 may be used to accommodate different sizes of boilers.

I claim:

110 1. In a device of the class described, a stove body having an opened top formed with an inwardly projecting flange, a boiler

insertible through the top opening into the stove body, means provided in the latter to support the boiler, a removable rim portion supported by the flange of the stove opening and extending above the upper edge of the boiler, said rim portion being provided with an opening above the boiler, and a closure for the opening of the rim portion supported by the latter in a plane above the boiler.

5 2. In a device of the class described, a stove body, a top rim portion provided with an outlet leading from one side and an internal shoulder formed below the outlet, a boiler supported within the stove body, and a rim encircling the boiler and supported on the internal shoulder of the top rim portion below the side outlet, the inner edge of the second rim abutting the boiler and being provided with openings, those openings opposite the side of the boiler adjacent the side outlet being smaller than those openings opposite the other side of the boiler to thereby dampen the flow of heat on the first side

10 15 20

of the boiler and effect more even distribution of the heat about the boiler.

3. In a device of the class described, a stove body adapted to receive a wash boiler provided with the usual handles, a top rim portion on the body having end recesses, adapted to receive the handles of a wash boiler, and an internal shoulder provided below the recesses, and a rim seating on the shoulder adapted to encircle a wash boiler below its handles and close the surrounding space, said second rim being provided with openings on its opposite sides and being solid at its ends beneath the handles of a received wash boiler to prevent the handles being in direct contact with the heat.

25 30 35 In testimony whereof I affix my signature in presence of two witnesses.

ABRAHAM SHAPIRO.
